UNITED STATES PATENT OFFICE.

JAMES B. WHEATLEY, OF KANSAS CITY, MISSOURI.

COMBINATION FOLDING BED.

SPECIFICATION forming part of Letters Patent No. 759,788, dated May 10, 1904.

Application filed June 9, 1902. Serial No. 110,800. (No model.)

To all whom it may concern:

Be it known that I, JAMES B. WHEATLEY, a citizen of the United States, residing in Kansas City, in the county of Jackson and State of Missouri, have invented a new and useful Improvement in Combination Folding Beds, of which the following is a specification, reference being had therein to the accompanying drawings, forming a part thereof.

10 My invention relates to improvements in combination folding beds.

The object of my invention is to provide an article of furniture in which is combined a bed, a bookcase, and a wardrobe.

15 My invention has for its further object certain peculiarities of construction hereinafter fully described and claimed by means of which the wardrobe and the bookcase may provide means for support for the bed when 20 in use and which will when the bed is not in use serve to conceal it from view.

Other novel features of construction are hereinafter fully described and claimed.

In the accompanying drawings, which illustrate my invention, Figure 1 is a top view showing the parts when in a fully-closed position. Fig. 2 is a front elevation view of the same. Fig. 3 is a front elevation view showing the wardrobe and bookcase in the open 30 position with the bed swung to the upright position. Fig. 4 is a vertical sectional view looking toward the rear side of the wardrobe and taken on the dotted line *a b* of Fig. 3. Fig. 5 is a top view showing the wardrobe 35 and bookcase moved to the open position with the bed in the horizontal position. Fig. 6 is a front elevation view of the parts when in the position shown in Fig. 5. Figs. 7 and 8 are respectively rear elevation and top views 40 showing one end of a horizontal rod connecting the two side members. Figs. 9 and 10 are respectively side elevation and top views of one of the supporting-posts and the hinges connecting the same with the side members. 45 Similar numerals of reference indicate similar parts.

1 indicates an ordinary mattress-frame, 2 the mattress, and 3 and 4 a wardrobe and bookcase, respectively, forming the side members. 50 The side members are preferably rectangular

and are hinged, respectively, at their rear outer corners to the vertical posts 5, which with a transverse brace 6, connected with the posts, form a framework upon which the side members swing from a position parallel therewith to a position at right angles thereto. Each side member is provided with a mattress-supporting device on its rear side comprising, preferably, a drawer-pocket 7, which extends rearwardly from the lower end of the member 60 and is provided in its upper side with a cover 8, (shown in Fig. 5,) which can be raised for the insertion in the drawer 9, located in said pocket, of the bedclothes, pillows, &c. These extensions or drawer-pockets 7 also serve to 65 support the mattress-frame 1 when it is in the horizontal position. (Shown in Figs. 5 and 6.) The transverse brace 6 is mounted at its ends in clamping-rings 10, secured upon the posts 5 above the extensions 7. The brace 6 serves to 70 retain the posts 5 at a uniform distance apart. Each end of the brace 6 is bent downwardly and enters a vertical hole provided therefor in each ring 10. Mounted by hinges 11 on each post 5 is a vertical wing 12, provided on its 75 inner side above the extensions 7 with a transverse strip or cleat 13, adapted to support thereon the mattress-frame 1. As shown in Fig. 4, each inner corner on the rear side of the mattress-frame is provided with a curved 80 lug 14, on which the mattress-frame is rolled on the strips 13 when the mattress-frame is raised to the position shown in Fig. 4. On each wing 12 is provided on its inner side near the top and back thereof a projection 15, adapted to have rest thereon the mattress-frame 1 when it is in the raised position, and thus preventing its further rearward movement. Suitable casters 16 may be provided on the lower ends of the posts 5 and the side members 85 90 95 3 and 4.

In operating my invention the side members are swung from the parallel position shown in Fig. 1 to that shown in Fig. 5. The mattress-frame 1 is then lowered so that it rests upon the extensions 7 of the side members, the rear side of the bed resting upon the strips 13. If it is desired to pass behind the bed, the mattress-frame may be pulled forward and one of the wings swung around, so as to admit the 100

person behind the brace 6. When it is desired to close the parts, the mattress-frame 1 is pulled forward until the frame strikes against the brace 6, when the frame is rolled 5 on the lug 14 to the upright position, in which the mattress-frame rests against the pins 15 in a position slightly inclined to the rear. The side members 3 and 4 are then swung on the posts 5 to a position parallel with the 10 brace 6, in which position they will conceal the mattress-frame to the rear thereof, the combined width of the side members being substantially the distance between the posts 5. Before so swinging the side members the covers 8 of the extensions 7 may be raised and the pillows and other bedclothing may be placed in the drawers 9. Any desired means 15 may be employed for limiting the outward swing of the side members 3 and 4 and the 20 wings 12 upon the posts 5.

The mattress-frame is preferably arranged lengthwise between the members 3 and 4—that is, with the length parallel with the brace 6. The members 3 and 4 are shown as being 25 a wardrobe or clothes-press and a bookcase; but it is obvious that these members may be employed for such other purpose as may be desired, and their particular conformation may be such as will conform to the use intended.

30 With the construction employed in my invention three useful pieces of furniture are combined into what is practically one compact-piece that may be readily moved to any desirable position in the room containing it. When 35 closed, the article of furniture has the appearance of being simply a bookcase and wardrobe, the bed being concealed.

My invention may be modified in various ways without departing from its spirit.

40 Having thus described my invention, what I claim, and desire to secure by Letters Patent, is—

1. An article of furniture comprising two vertical posts, a transverse brace connecting 45 the posts, a mattress-frame, two wings hinged to the posts and provided with transverse strips on their inner sides located below the

transverse brace and adapted to have the mattress-frame resting thereon, means for limiting the rearward movement of the mattress-frame when it is swung to an upright position on the said strips, and two side members hinged respectively to the two posts, and provided each with a rearward extension adapted to receive thereon, when the side members are 55 in the proper position, the said mattress-frame, substantially as described.

2. An article of furniture comprising two posts, a transverse brace connecting the posts, two wings hinged to and in the rear of the 60 two posts respectively, and provided each with means adapted to support thereon a mattress-frame, and having also means for limiting the movement of the mattress-frame when placed in the upright position, and two side members 65 hinged to the two posts in front thereof respectively, each side member being provided with a rearward extension adapted to support thereon the mattress-frame when the side members are swung to the proper position, 70 substantially as described.

3. An article of furniture comprising two vertical posts, a transverse brace connecting the same, a mattress-frame, two wings hinged to the two posts respectively and provided 75 each with means adapted to support thereon the mattress-frame and provided each also with means for limiting the movement of the mattress-frame when placed in the upright position, and two side members comprising respectively a wardrobe and a bookcase hinged to the two posts in front of the said wings and provided each with a rearward extension adapted to support thereon the mattress-frame when the bookcase and wardrobe are 80 swung to the proper positions, substantially as described.

In testimony whereof I have signed my name to this specification in presence of two subscribing witnesses.

JAMES B. WHEATLEY.
